UNITED STATES PATENT OFFICE

151,471

DESIGN FOR A GAS REGULATOR

Theodore A. St. Clair and William R. Eddy, Bartlesville, Okla., assignors to Phillips Petroleum Company, a corporation of Delaware

Application January 14, 1946, Serial No. 125,547

Term of patent 14 years

(Cl. D52—2)

To all whom it may concern:

Be it known that we, Theodore A. St. Clair and William R. Eddy, both citizens of the United States, residing at Bartlesville, in the county of Washington and State of Oklahoma, have invented a new, original, and ornamental Design for a Gas Regulator, of which the following is a specification, reference being had to the accompanying drawing, forming part thereof.

Figure 1 is a front elevational view of a gas regulator, embodying our new design;

Figure 2 is a top plan view of the regulator shown by Figure 1; and,

Figure 3 is a perspective view of the regulator shown by Figure 1.

We claim:

The ornamental design for a gas regulator, as shown

THEODORE A. ST. CLAIR.
WILLIAM R. EDDY.
